Attorney

UNITED STATES PATENT OFFICE.

ANDREW W. GRAHAM, OF BUFFALO, NEW YORK, ASSIGNOR TO CITY TRUST CO.,
BRANCH OF THE MARINE TRUST CO. OF BUFFALO, TRUSTEE, OF BUFFALO,
NEW YORK.

PACKET OR CARTON.

1,414,944.

Specification of Letters Patent. Patented May 2, 1922.

Application filed December 8, 1920. Serial No. 429,238.

To all whom it may concern:

Be it known that ANDREW W. GRAHAM, a citizen of the United States of America, residing at Buffalo, in the county of Erie

5 and State of New York, has invented certain new and useful Improvements in Packets or Cartons, of which the following is a specification.

This invention relates to packets or boxes 10 and has special reference to a box or carton designed particularly for receiving and holding matches and the like although it is to be understood that various other articles may be packed in boxes constructed as is this.

15 One important object of the invention is to provide an improved general construction of box of this character the same being an improvement on my prior Patent 1,351,242.

A second important object of the invention 20 is the provision of an improved box of this character so constructed and arranged that it may be cheaply and readily constructed out of such material as card board, press board or the like.

25 A third important object of the invention is to construct a box of this description in an improved manner so that the matches or other like articles may be carried on a rib disposed centrally between the two halves 30 of the box whereby easy access may be had to such matches whenever it is desired to withdraw one or more.

A fourth important object of the invention 35 is the provision of an improved box of this character constructed from a single piece of sheet material pressed and folded in a novel manner to provide all the necessary parts of the box.

With the above and other objects in view, 40 as will be hereinafter set forth, the invention consists in general of certain novel details of construction and combinations of parts hereinafter fully described, illustrated in the accompanying drawings and specifically 45 claimed.

In the accompanying drawings like characters of reference indicate like parts in the several views, and:—

Figure 1 is a perspective view of the complete 50 box with matches held therein, the view showing the position assumed by such matches when the box is open.

Figure 2 is a transverse section through one form of the box wherein the two halves 55 are made from separate pieces of material.

Figure 3 is a transverse section through a second form of box, the whole being made from a single piece of sheet material.

Figure 4 is a transverse section through a third form of box having a peculiar form 60 of article support.

Figure 5 is a transverse section through a fourth form of box having a special hinge arrangement.

In the particular embodiment of the invention herein illustrated each form consists of two similar sides and a central rib. Each side portion consists of a flat central part 10 surrounded by side walls 11 arcuate in cross section and is formed by pressing a sheet of 65 plastic material such as cardboard or the like between suitable dies. Each of these side portions may, if desired, be provided with a finger tab 12 projecting from its free edge.

From the edges opposite the tabs 12 extend the parts forming the central rib. In Figure 2 this rib consists of two separate strips 13 each formed integrally with a respective side and firmly glued together. In this, as in the remaining instances, the rib 70 portions are connected to the sides by fold lines 14 to form hinge portions.

In the form shown in Figure 3 both sides and the rib are formed from a single piece of the material, the rib being formed by 85 doubling, as at 15, the material between and connecting the two sides so that the doubled portions lie back to back as at 16.

In the form shown in Figure 4 the portion of the blank connecting the two sides is 90 doubled to form the central rib but the inner edge of this rib pressed backward toward the hinges by suitable means to produce a channel 17 supported on a rib 18.

In each instance the rib is slotted as at 19 95 and through these slotted portions pass elastic strands 20 connected at their ends to respective sides so that the sides are normally held closed. Also each form is provided with strips of abrasive material 21 at the 100 hinge portions, these strips serving the double function of reinforcing the parts and proving a striking surface for matches 22 which, in Figures 2 and 3, are shown as having their butts bunched together and straddling the rib to which they may be attached by adhesive if desired.

In the form shown in Figure 4 the butts of the matches are held between the side walls or flanges of the channel and the ends 110

may be glued, if necessary, to the web of such channel. In this form especially it is to be noted that various articles may be suitably packed in the device. For instance a 5 change in the size of the box and proportions of the channel would readily adapt the box for cigarettes.

There has thus been provided a simple and efficient device of the kind described and for 10 the purpose specified.

It is obvious that many minor changes may be made in the form and construction of the invention without departing from the material principles thereof. It is not, therefore, desired to confine the invention to the exact form herein shown and described but it is wished to include all such as properly come within the scope claimed.

Having thus described the invention, what 20 is claimed as new, is:—

1. The herein described carton consisting of a sheet of foldable material having end portions and a central portion, said end portions being pressed to form carton sides, said 25 central portion being doubled upon itself to extend inwardly between the sides and thereby form an inwardly projecting rib for the attachment of articles to be packed in said carton.

2. The herein described carton consisting of a sheet of foldable material having end portions and a central portion, said end portions being pressed to form carton sides, said 30 central portion being doubled upon itself

to form an inwardly extending rib, the inner 35 edge of said rib being involuted to form a channel for the reception of the ends of articles to be held in said carton.

3. The herein described carton consisting of a sheet of foldable material having end 40 portions and a central portion, said end portions being pressed to form carton sides, said central portion being doubled upon itself to extend inwardly between the sides and thereby form an inwardly projecting rib for 45 the attachment of articles to be packed in said carton, said sides being defined from the rib portions by hinge lines, and elastic strands connecting the sides near the hinge line, said rib portions being slotted to permit passage of the strands therethrough.

4. The herein described carton consisting of a sheet of foldable material having end 50 portions and a central portion, said end portions being pressed to form carton sides, 55 said central portion being doubled upon itself to form an inwardly extending rib, the inner edge of said rib being involuted to form a channel for the reception of the ends of articles to be held in said carton, said sides 60 being defined from the rib portions by hinge lines, and elastic strands connecting the sides near the hinge lines, said rib portions being slotted to permit passage of the strands therethrough.

65 In testimony whereof I affix my signature.

ANDREW W. GRAHAM.
